I. FOX

EYE EXERCISING DEVICE

Filed May 27, 1926

INVENTOR.

Ivan Fox
BY Cyrus A. Anderson

ATTORNEY.

UNITED STATES PATENT OFFICE.

IVAN FOX, OF MEDIA, PENNSYLVANIA, ASSIGNOR TO ANNA E. FOX, OF MEDIA, PENNSYLVANIA.

EYE-EXERCISING DEVICE.

Application filed May 27, 1926. Serial No. 111,935.

Persons frequently have trouble with their eyes due to some defective muscular condition. It may be that all of the muscles of the eyes for some reason or other have become 5 weakened or it may be that one set of muscles, due to the conditions under which the eyes are used, will have received sufficient exercise to keep them in proper condition while another set will remain undeveloped. 10 This is particularly true with respect to those muscles which control the movements and the positions of the eyes in their respective sockets.

In order to correct such deficiencies of 15 muscular development it frequently is necessary that persons use or manipulate their eyes in a way to exercise the muscles thereof or in a way to exercise particular muscles which may require special exercises to effect 20 proper development of the muscles thereof and to effect correction of the deficiencies therein.

Heretofore the means employed for effecting such exercises have consisted of lenses so 25 made as to require the person using the same to put forth considerable muscular energy to overcome the effect of the lenses upon the eyes,—the employment of which furnishes the exercise necessary to develop the particular 30 muscles desired to be developed by the lens or lenses.

The providing of such lenses requires the expenditure of a considerable amount of 35 money, making it difficult in many cases for persons of limited means to follow the directions of a physician to obtain such lenses and use the same in exercising the muscles of the eyes.

The general object of my invention is to 40 provide a novel mechanical device which is simple in construction and which may be employed for exercising the muscles of the eyes.

It also is an object of the invention to provide 45 a device of novel construction including means which may be adjusted from one position to another in order to vary or change the exercises to which the eye muscles may be subjected.

A further object of the invention is to provide 50 a device of novel construction having means whereby the muscles of the eyes may be exercised in different planes, which planes may be vertical, horizontal, or along any plane or line at any angle in between said 55 vertical and horizontal planes.

To these and other ends my invention comprehends the construction and arrangement of parts as hereinafter described in detail, particularly pointed out in the claims and as illustrated in the drawing accompanying and forming a part of this specification and in which—

Fig. 1 is a view in front elevation;

Fig. 2 is a view in vertical sectional elevation taken on the line 2—2 of Fig. 1; 65

Fig. 3 is a view in front elevation of the upper portion of the device with a member of said upper portion readjusted and supported in a different position from that in which it is supported in Fig. 1; and 70

Fig. 4 is a view in vertical sectional elevation taken on the line 4—4 of Fig. 3.

Referring to the drawing it will be noted that the device comprises a base 1 from which rises a post or standard 2 which may be tubular, as indicated. The upper end of the said post or standard is provided with four slots 3 arranged in 90° angular relation with respect to each other. The said upper end may be slightly compressed so as to cause 80 the same to fit more or less closely about the end portion 4 of a stem 5 which projects thereinto. The stem 5 is provided with a narrow collar or flange-like member 6 which is secured thereon at a point a short distance 85 from its outer end. The presence of the said collar or flange limits the extent of entry of the said stem into the upper end of the post or standard 2. The opposite or upper end of the stem 5 is provided with a tubular sleeve 8 which extends in right angular relation thereto, the said stem and sleeve constituting a T-shaped member. The opposite ends of the sleeve 8 are provided with narrow slots 10 arranged in 90° angular relation 90 to each other. Mounted within the said sleeve is a rod or bar 12. The opposite ends of the said sleeve 8 are slightly compressed so as to cause them to frictionally bear 95 against and hold the said rod 12 in positions to which it may be adjusted in the said sleeve. To facilitate rotative adjustment of the rod 12 I have provided it with a narrow collar or flange-like member 13 adjacent one 100 end thereof. At the opposite end I have provided a hole 15 which extends transversely therethrough through which a rod 16 extends. The said rod 16 is adjustable 105 lengthwise and is provided at its opposite ends with objective members 17 consisting of 110

balls or enlargements of other form which may be of any color desired. The rod 16 may be held in any position to which it may be adjusted by means of a binding screw 18 terminating at its outer end in a knurled disk 19 which constitutes an intermediate objective member and which may be of the same color, for instance black, as that of the objective members 17, previously referred to. 10 The said binding screw is in engagement with a threaded opening 20 located in the forward end of the rod or bar 12 and extending axially thereof.

It will be noted that the rod 12 upon which the rod 16 is mounted is rotatable within the sleeve 8, so that the rod 16 may be adjusted into different angular positions about the axis of the said rod or bar 12, as is indicated in dotted lines in Fig. 1 of the drawing. As previously set forth, the rod 16 may be revolved by the rotation of the rod or bar 12 into any angular position which may be desired. The stem 5 which constitutes in Figs. 1 and 2 a continuation of the post or standard 2 may also be rotated in either direction so as to adjust the rod or bar 12 and the rod 16 into different angular positions with respect to the vertical axis of the post 2 and stem 5. 25 It will be apparent that when the rod or bar 12 is rotated in the sleeve 8 the rod 16 is moved in a vertical plane parallel to the axis of the post or standard 2. As already indicated, the rod 16 may be adjusted lengthwise so as to vary its point of connection to the rod or bar 12 with respect to the opposite ends thereof.

The construction as shown in Figs. 3 and 4 is identical with that shown in Figs. 1 and 2, except that the end portion 22 of the rod or bar 12 which extends beyond the knurled finger piece 13 is inserted into the upper end of the post or standard 2. When the end portion 22 is inserted into the upper end of the post 2 the collar or flange-like member 13 operates as a stop to limit the extent to which the cross bar 12 may enter the opening in the upper end of the said post. In the construction as shown in Figs. 1 and 2, the rod 16 may not only be revolved or moved around the axis of the rod or bar 12 in a vertical plane parallel to the axis of the standard 2, but it may also be revolved around the axis of the said standard 2. The latter movement may be effected by rotating the stem 5. In the arrangement as shown in Figs. 3 and 4 the rod 16 may be adjusted lengthwise and may also be revolved or rotated in a horizontal plane about the axis of the post or standard 2. In the arrangement as shown in Figs. 1 and 2, three objects to be looked at by a person using the device for exercising the eyes are provided. These consist of the objective members or enlargements 17 and the head 19 of the binding

screw 18, whereas in the arrangement as shown in Figs. 3 and 4 only two objects are provided to be looked at by a person using the device, namely, the objective members 17.

When a person is using the device he 70 places it in front of his eyes and then, while holding the head in fixed position, either moves both eyes or one eye alone slowly back and forth so as to observe alternately the objective members previously referred to. 75 In doing this the muscles of the eyes are exercised and may be extended, thereby increasing the blood circulation which effects a general toning up of the eye condition.

It will be seen that by my invention I am 80 enabled to provide a mechanical device of simple construction which may be employed as a means for effecting exercise of the muscles of the eyes and that such device is of a character such that it may be manufactured 85 and sold at a minimum price.

Having thus described my invention, what I claim and desire to secure by Letters Patent is:

1. A device for exercising the eyes comprising a support, a vertical rotatable stem mounted upon the upper end of said support, rotatable bar mounted upon said stem and extending transversely thereof, and a rod supported by said bar and occupying a 90 vertical plane parallel to the axis of the said support.

2. A device for exercising the eyes comprising a supporting post, a stem rotatably mounted upon the upper end of said post, the axes of the post and stem being in alignment, a bar rotatably mounted upon the upper end of said stem, and a rod mounted upon the said bar, which rod extends at right angles to the said bar and is adjustable 100 lengthwise.

3. A device for exercising the eyes comprising a vertical post, a stem rotatably mounted upon the upper end of said post and constituting an extension thereof, a bar 110 rotatably mounted upon the upper end of said stem and extending substantially at right angles thereto, and a rod mounted upon the said bar and extending substantially at right angles thereto, the said rod being adjustable lengthwise and terminating at its opposite ends in objective members.

4. A device for exercising the eyes comprising a vertical post, a rod supported upon said post, said rod being provided with objective members located a substantial distance from each other, and means whereby said rod is adapted to be rotated in a plane parallel with the axis of said rod and which rod also is adapted to be revolved about the 120 said axis.

5. A device for exercising the eyes comprising a vertical post, a rod mounted upon the upper end of said post, said rod being provided with objective members supported 130

thereon a substantial distance from each other, means whereby the said rod is adapted to be rotated in a plane parallel to the axis of said post and which rod also is adapted to be revolved around the axis of said post, and an objective member located intermediate the first named objective members.

6. A device for exercising the eyes comprising a T-shaped member the cross bar of which is rotatably mounted upon the upper end of the stem thereof which cross bar is provided at one end with a rod adjustably connected therewith and extending at right

angles thereto, said rod having objective devices mounted thereon a substantial distance from each other and the opposite end portion of the said cross bar and the lower end portion of the said stem each having near its end a collar and means adapted to receive either of the said end portions whereby the said member may be rotatably supported.

In testimony that I claim the foregoing as my invention, I have hereunto signed my name this 25th day of May, A. D. 1926.

IVAN FOX.
